UNITED STATES PATENT OFFICE.

WALTER H. COTTON, OF CHICAGO, ILLINOIS, ASSIGNOR TO UNION DRAFT GEAR COMPANY, OF CHICAGO, ILLINOIS, A CORPORATION OF DELAWARE.

DRAFT GEAR.

Application filed July 30, 1925. Serial No. 46,950.

The invention relates to draft gears of the friction type, for railway cars, its object being to secure simplicity and cheapness of manufacture and high efficiency.

5 A preferred embodiment of the invention is illustrated in the accompanying drawings, in which

Fig. 1 is a plan view of the gear as applied to a car, some parts being shown in 10 section;

Fig. 2 is a side elevation, some parts being broken away, and other parts being shown in section, the gear being shown under compression;

15 Fig. 3 is a side elevation of the gear, in release;

Fig. 4 is a transverse median vertical section of the gear applied to the draft sills of a railway car;

20 Fig. 5 is a view in perspective of one of the elements of the gear;

Figs. 6 and 7 are details in perspective of certain of the elements of the gear; and

25 Figs. 8 and 9 are a plan view and side elevation respectively of the gear showing a modified form of construction.

For the purpose of showing the manner of mounting the gear on a car there is shown a 30 pair of draft sills at 10; a top plate connecting the sills, at 11; a bottom tie plate and gear support at 12; a conventional form of yoke for enclosing the gear, at 13; and the butt of a coupler at 14. A pair of draft lugs 15, 16 and a pair of buffering lugs 17, 35 18 are also shown. These elements however form no part of the present invention.

The improved gear comprises a pair of 40 similar followers 19, 20 adapted for engagement respectively with the draft and buffering lugs and provided with transverse converging wedging faces 21, 22 and the side flanges 23, 24. Cooperating with the wedging faces of each of the followers is a pair of wedge blocks or bars 25 which are of 45 such length that they make a loose fit with the side walls of the followers, these walls serving to retain them in proper position.

Located on the central transverse median line of the gear is a tension rod 50 of sufficient length to extend through and beyond the sills 10 and carry on its end portions expansion springs 26, 27 which react between seats 28, 29 in the form of nuts threaded upon the ends of the rod, and seats

30, 31 sleeved upon the rod and having stems 55 which project through the sill slots.

Seated against the inner end of each of the last named spring seats and frictionally engaging the blocks 25, 25, is a wedge block 32, the inner face of which is horizontally 60 recessed and provided with wedge faces 33, 34. Interposed between the blocks 32, 32 are a pair of wedging elements 35, which overlap the blocks 25, 25, one thereof co-operating with the upper and the other with 65 the lower wedging faces of the blocks 32, 32. Preferably the blocks 32, 32 are vertically recessed centrally across their wedging faces, as indicated at 36, and the elements 35 are provided with lateral projections as 37 for 70 entering these recesses, thereby interlocking the elements referred to against relative longitudinal movement. Each of the elements 35 is transversely recessed in its lower face as indicated at 38 to accommodate the rod 75 50, the projections 37 compensating for the weakening effect of this recess. The length of the elements 35, 35 is such that they overlap the blocks 25, 25 without however bearing against the inner vertical faces thereof. 80

Normally the springs 26, 27 hold the wedge blocks 32, 32 at the limit of their inward movement, the elements 35, 35 being urged downwardly and upwardly respectively to the limit of their movement, that is 85 until they substantially contact with the rod 50, and the followers 19, 20 being thereby urged backwardly and into engagement respectively with the draft and buffering lugs. 90

Under the influence of either draft or buffering stresses, one of the followers is moved inwardly or toward the other follower, forcing outwardly the blocks 25, 25. The elements 35, 35 are thereby forced apart, moving upwardly and downwardly respectively and thus forcing apart or laterally outward the wedge blocks 32, 32 against the resistance of the springs 26, 27. The inner faces of the blocks 25, 25 bear against end faces of 100 the blocks 32, 32 and the friction between them is very heavy, and is the greater because of their twofold relative movement, the former moving vertically and the latter horizontally. Friction is developed between the various cooperating wedging faces, and between the blocks 25, 25 and the elements 32, 32, of sufficient intensity to give the gear 105

high capacity. All of the elements of the gear, with the exception of the springs and tension rod, may be of cast metal and capable of use without machining.

- 5 The followers 19, 20 are provided with forwardly extending side flanges 40, 41 of such length that they make contact with the ends of the blocks 32, 32 when the gear is under full compression.
- 10 While the preferred form of construction has been described various changes in detail may be made without departing from the scope of the invention, as for example, the two sets of elements 25, 25 and 35, may be 15 cast integrally as shown in Figs. 7 and 8. In this construction however the advantage of frictional engagement between the elements 25, 25 and 32, 32 is lost.

I claim as my invention:

- 20 1. In a draft gear in combination, a pair of opposed followers, V-shaped wedges associated with the followers, a pair of wedge blocks engaging the wedge faces of each of the first named wedges, a pair of elements 25 each overlapping a pair of the second named wedges at opposite ends of the gear, such elements having wedging faces laterally disposed with reference to the axis of the gear, a pair of wedge blocks cooperating with the 30 wedge faces of each of the last named elements and frictionally engaging a pair of the second named wedges, and spring means resisting the outward lateral movement of the last defined wedge blocks.
- 35 2. In a draft gear, in combination, a pair of opposed followers, a transverse tension rod, a pair of expansion springs mounted on the end portions of the rod and expanding inwardly, wedging elements cooperating by 40 their wedging engagement for compressing the springs, and sets of wedging elements associated one with each of the followers and acting by their wedging engagement to cause the wedging action of the first-named 45 wedging elements.
3. A pair of longitudinally movable fol-

lowers each having a spreading wedge associated therewith, a pair of wedge blocks cooperating with each of the spreading wedges and each having an inner face normal to 50 the axis of the gear, a pair of laterally movable wedge blocks interposed between the first named blocks at each end of the gear, wedging elements for urging outwardly the 55 last named wedge blocks and being actuated by the first named blocks, and spring means resisting the outward movement of the second named blocks.

4. A pair of opposed followers each having a V-shaped wedging face, floating wedge 60 blocks engaging each of such faces and each having an inner face normal to the axis of the gear, a pair of laterally movable blocks interposed between and frictionally engaging the floating blocks at opposite ends of 65 the gear, each of the interposed blocks having a V-shaped recess in its inner face, a pair of wedging elements cooperating with the faces of such recesses and bearing on the outer faces of the floating blocks, and spring means opposing the outward movement of the interposed blocks.

5. A pair of opposed followers each having a V-shaped wedging face, floating wedge 70 blocks engaging each of such faces and each having an inner face normal to the axis of the gear, a pair of laterally movable blocks interposed between and frictionally engaging the floating blocks at opposite ends of 75 the gear, each of the interposed blocks having a V-shaped recess in its inner face, a pair of wedging elements cooperating with the faces of such recesses and bearing on the outer faces of the floating blocks, and spring 80 means opposing the outward movement of the interposed blocks, the followers having forwardly extending side flanges for engaging the ends of the interposed blocks when the gear is fully compressed.

In testimony whereof I affix my signature.

WALTER H. COTTON.
